(57) **CLAIM**

The ornamental design for a consumer electronics device as shown and described.

DESCRIPTION

FIG. 1 is a front side perspective view of a consumer electronics device in a fully retracted configuration.

FIG. 2 is a back side perspective view of the consumer electronics device in the fully retracted configuration.

FIG. 3 is a second front side perspective view of the consumer electronics device in the fully retracted configuration.

FIG. 4 is a front plan view of the consumer electronics device in the fully retracted configuration.

FIG. 5 is a back plan view of the consumer electronics device in the fully retracted configuration.

FIG. 6 is a right side plan view of the consumer electronics device in the fully retracted configuration.

FIG. 7 is a left side plan view of the consumer electronics device in the fully retracted configuration.

FIG. 8 is a top side plan view of the consumer electronics device in the fully retracted configuration.

FIG. 9 is a bottom side plan view of the consumer electronics device in the fully retracted configuration.

FIG. 10 is a front side perspective view of the consumer electronics device in a fully extended configuration.

FIG. 11 is a front side plan view of the consumer electronics device in the fully extended configuration; and, FIG. 12 is a left side plan view of the consumer electronics device in the fully extended configuration.

The broken line showing of internal surfaces is for the purpose of illustrating internal portions of the consumer electronics device and forms no part of the claimed design.
